INVENTOR

BY Victor J. Evans

ATTORNEY

John Miller Peter
WITNESS:

UNITED STATES PATENT OFFICE.

LAWRENCE M. DE WITT, OF ASHTABULA, OHIO.

GUIDE AND SIGN POST.

1,355,036.

Specification of Letters Patent.

Patented Oct. 5, 1920.

Application filed February 24, 1920. Serial No. 360,988.

To all whom it may concern:

Be it known that I, LAWRENCE M. DE WITT, a citizen of the United States, residing at Ashtabula, in the county of Ashtabula and 5 State of Ohio, have invented new and useful Improvements in Guide and Sign Posts, of which the following is a specification.

This invention relates to display devices, particularly to advertising guide posts, and 10 has for its object the provision of a combined advertising sign and direction guide post adapted particularly for use along highways and bearing indicia as to the direction and distance of a nearby town or 15 the like and also provided with a plurality of panels upon which the name and address of a firm may be painted and upon which various separate advertisements may also be painted.

20 An important object is the provision of a device of this character in which the advertisement bearing panels are each formed of sheet-metal so bent or looped as to provide a rigid structure not likely to be bent under 25 ordinary conditions, each panel further having associated therewith a diagonal brace which holds the sides of the panels in proper relation and which has its end portions engaged beneath overlapping portions of the 30 panels and bolted thereto, this structure insuring great strength.

An additional object is the provision of a device of this character which will not only be an efficient guide as to direction and 35 distance but which will also display the desired advertising matter in a very neat and efficient manner without in any way marring the landscape.

With the above and other objects and 40 advantages in view, the invention consists in the details of construction to be herein-after more fully described and claimed, and illustrated in the accompanying drawings, in which—

45 Figure 1 is a front elevation of my device,

Fig. 2 is a rear elevation,

Fig. 3 is a detail cross sectional view taken through the guide panel at its point 50 of connection with the standard,

Fig. 4 is a cross sectional view taken along the points of connection of one of the brace members with a panel,

Fig. 5 is a detail cross sectional view through the outer end of a panel, and 55

Fig. 6 is a front elevation showing a slightly modified form of device.

Referring more particularly to the drawings, the numeral 10 designates a standard which may be a wooden post, preferably 60 square in cross section, and which is anchored or embedded within a concrete post, not shown, sunk into the ground. At its upper end the standard 10 carries any suitable cap 11 which may be made as ornamental as desired. Adjacent the cap 11 the standard 10 is recessed at one edge, as shown at 12, and seated within this recess and flush with the edge of the standard is a wooden block 13 against which is secured 65 an elongated panel 14 formed of metal and having painted thereon indicia as to the direction and distance of a nearby town or the like. This panel 14 is formed flat and has its sides and ends 15 and 16 bent against 70 its rear face, as clearly shown, for the purpose of stiffening the panel.

Secured upon the standard 10, one above another and in spaced relation, are panels 75 17 and 18 which may be of the same size if 30 desired though it is preferable that the uppermost and lowermost panels 17 be narrower than the intermediate panels 18. Each of the panels 17 and 18 is formed of a sheet of metal, preferably galvanized iron 85 bent to provide similar portions extending at right angles to each other. The bend is abrupt so that the panels will fit neatly against an edge of the standard and these panels are secured in position by screws 19 90 passing therethrough and into the standard 10. The panels 17 are adapted to have painted thereon the name and address of the firm using the device and the panels 18 are intended to have painted thereon any 95 desired advertising matter.

Each of the panels 17 and 18 has its top and bottom edges bent against the rear thereof, as shown at 20, and has its side edges or ends bent against the rear face, as 100 shown at 21, it being observed that the bent portions 20 being bent upon themselves at the ends provide four thicknesses of material at each corner of each panel which insures rigidity in so far as buckling or 105 warping is concerned. Each panel 17 and

18 has associated therewith a diagonal brace bar 22 which extends between the end portions of the panel and which has angular ends 23 engaged between the body of the sheet forming the panel and the bent end portion 21 between the bent portions 20, and these angular ends 23 of the bars are secured to the panels by bolts 24 equipped with suitable nuts 25.

10 In some instances the advertiser may find it preferable to use a single advertising panel instead of the plurality of panels above described. In such an event the arrangement is as shown in Fig. 6. In this figure the 15 panels 18, previously described, are replaced by a single panel 26 of identically the same construction but of a size equal to the plurality of panels taken together. The advertising matter may be painted directly upon 20 this panel 26 or might be in the form of separate signs or cards fastened thereto by any suitable means.

From the foregoing description and a study of the drawings it will be apparent 25 that I have thus provided a simply constructed and consequently inexpensive combination direction guide and display device which will be strong and which will moreover be neat and attractive in appearance 30 so as to convey the desired information without being a blot upon the landscape.

While I have shown and described the preferred embodiment of my invention, it is of course to be understood that I reserve 35 the right to make such changes in the form,

construction, and arrangement of parts as will not depart from the spirit of the invention or the scope of the subjoined claim.

Having thus described my invention, I claim:

A device of the character described comprising a vertical standard rectangular in cross section, and a plurality of panels secured thereon one above another and in spaced relation, said panels being adapted 45 to bear legends and each being formed from a sheet of metal bent transversely whereby to provide portions extending at right angles to each other, the bend of each panel being disposed at the edge of the standard 50 with said right angularly extending portions bearing flat against and secured to adjacent faces of the standard, the upper and lower edges of the sheet forming each panel being bent backwardly against the body of the panel to provide longitudinal reinforcements and the ends of each sheet being bent 55 backwardly upon the body and upon said first named bent portions whereby to provide transverse reinforcements, a diagonal brace member associated with each panel and having angular ends engaged between said second named bent portions and the body of the sheet between said first named bent portions, and securing members passing through the angular end portions of the braces and through the body of the panel and said second named bent portions.

In testimony whereof I affix my signature.

LAWRENCE De WITT.
